FUSE PLUG ASSEMBLY

George M. B. Sener, Pontiac, and Thomas New-
man, Drayton Plains, Mich.

Application April 9, 1936, Serial No. 73,560

14 Claims. (Cl. 200—119)

This invention relates to a fuse plug assembly and has for its object to provide, in a manner as hereinafter set forth, whereby the elements therefor are so constructed and arranged relative to each other as to prevent surreptitious tampering therewith.

A further object of the invention is to provide, in a manner as hereinafter set forth, a fuse plug assembly including a non-tamperable fuse and adapter.

A further object of the invention is to provide, in a manner as hereinafter set forth, a fuse plug assembly including a non-tamperable fuse plug cutout base.

A further object of the invention is to provide, in a manner as hereinafter set forth, a fuse plug assembly having as an element thereof a non-removable adapter.

A further object of the invention is to provide, in a manner as hereinafter set forth, a fuse plug assembly having as an element thereof an adapter capable of being anchored in and non-removable from a fuse plug cutout base or panel now generally employed in connection with a fuse plug.

A further object of the invention is to provide, in a manner as hereinafter set forth, a fuse plug assembly including as an element thereof an adapter formed of a pair of sections and with one of the sections forming an element of the block with which the fuse plug is associated.

Further objects of the invention are to provide, in a manner as hereinafter set forth, a fuse plug assembly which is comparatively simple in its construction and arrangement, strong, durable, compact, thoroughly efficient in its use, non-tamperable and comparatively inexpensive to manufacture.

To the above ends essentially and to others which may hereinafter appear, the invention consists of the novel construction, combination and arrangement of parts as will be more specifically described and are as illustrated in the accompanying drawings wherein embodiments of the invention are shown, but it is to be understood that changes, variations and modifications may be resorted to which fall within the scope of the invention as claimed.

In the drawings:

Figure 1 is a front elevation of a fuse plug assembly in accordance with this invention, with the cover removed.

Figure 2 is a section on line 2—2, Figure 1.

Figure 3 is a side elevation of the fuse plug.

Figure 4 is an inverted plan view of the fuse plug.

Figure 5 is a side elevation of a modified form of fuse plug assembly.

Figure 6 is a vertical sectional view of the form 5 of assembly shown in Figure 5.

Figure 7 is a section on line 7—7, Figure 6.

Figure 8 is a top plan view of the adapter forming an element of the assembly shown in Figure 6.

Figure 9 is an inverted plan view of one of the sections of the adapter shown in Figure 6.

Figure 10 is a perspective view of the fuse member as it would appear before being blown.

With reference to Figures 1 and 2 of the drawings, the assembly includes a substantially square fuse block generally indicated at 10 and formed with rounded corners. The block is formed of an outer and an inner section 11, 12 respectively. The said sections are of square contour. The section 11 includes an outer part 13 and an inner part 14. The said parts are of square contour. The part 13 has rounded corners. The part 14 extends laterally from each of the sides of the part 13. The part 13 is formed with four equally spaced aligning circular sockets 16, only two of which are shown. The sockets open at the outer face of the part 13. The latter is also provided with four semi-oval shaped sockets 17 extending laterally from and communicating with the sockets 16. The width of the sockets 17 is materially less than the diameter of the sockets 16. The sockets 17 are arranged in opposite extending pairs. The bases of the sockets 16 and 17 align with the upper face of the part 14. 35

The part 14 has its upper face formed with four circular cutouts 18 (only two of which are shown). The cutouts 18 are disposed concentrically with respect to and are of less diameter than the sockets 16. The cutouts 18 communicate with the sockets 16 through the bases of these latter. The part 14 is formed with four annular grooves 19 (only two of which are shown). The grooves 19 are arranged inwardly with respect to the cutouts 18. The outer walls 20 of the grooves 19 form continuations of the walls of the cutouts 18. The depth of the grooves 19 is less than half the thickness of the part 14. The latter is formed with four circular passages 21 (only two of which are shown) and they are arranged to align with the axes of the sockets 16. Each passage 21 is disposed centrally with respect to a cutout 18. The wall of each passage 21 is upon two different diameters, the smallest of which is indicated at 22 and the largest at 23. The junc- 50

tion of the different diameter wall portions of the passages 21 provides the part 14 with internal shoulders 24. The edges of the portions of the part 14 between the inner walls of the grooves 19 and the wall portions 22 are toothed, as at 25. The part 14, in its lower face, is formed with an annular groove 26. The part 14 is formed with four openings 27 (only two of which are shown) which extend from the bases of the sockets 17 to the top wall 28 of groove 26. The lower face of the part 14 is provided with four annular grooves 29 (only two of which are shown) and said grooves 29 are materially less in depth than the groove 26. Each groove 29 encompasses in spaced relation the inner end of a passage 21. The upper face of part 14 is provided with three spaced pairs of spaced cutouts. The cutouts of one pair are indicated at 30, 31, the cutouts of another pair at 32, 33 and the cutouts of the other pair at 34, 35. The purpose of said cutouts will be presently referred to. The bottom of part 14, axially thereof, is formed with a squared lug 36.

The section 12 is of square contour and has its edges flush with the edges of the part 14 of section 11. The section 12 has the marginal portion of its outer face rabbeted throughout, as at 37. The outer face of the section 12, inwardly of the rabbet 37, is cut out, as at 38, and communicating with said cutout are four rectangular sockets 39 (only two of which are shown). The outer face of the section 12 is formed with a pocket 40 arranged between the inner ends of the sockets 39.

The portion 41 of the part 14 is mounted in the rabbet 37 and is provided with screw threaded openings 42. The portion 43 of the section 12 extends into the groove 26 and is spaced from the top or outer wall 28 of groove 26. The portion 44 of part 14 extends into the cutout 38 of section 12. The lug 36 extends into pocket 40. The inner ends of the passages 21 open into the sockets 39 centrally of the latter.

The part 13 is integral with the part 14. The part 14 is independent of the section 12. The part 14 and section 12 are connected together by the holdfast means 45. The block 10 is formed with openings 46 at its corners. The openings 46 extend through the part 14 and section 12 and are adapted to receive suitable holdfast means for anchoring the block 10 to a support.

Mounted against the base or inner wall of each socket 16 is an annular contact member 47 having its inner edge flush with the wall of the cutout 18. Integral with and extending from the outer edge of the contact 47 is a semi-oval shaped apertured stem 48 which is seated upon the base or inner wall of a socket 17. Mounted upon the base of the cutout 30, cutout 31, cutout 34 and the cutout 35 is a conducting plate 49 which extends into the groove 26 and has its inner portion aligning with stem 48. Each stem 48 is electrically connected to a plate 49 by a threaded headed metallic holdfast device 50 which extends through an opening 27 and engages in the plate 49. The plates 49 are spaced from section 12 by the portion 41 of part 14. The plate 49 is anchored to the portion 41 of part 14 by a threaded holdfast device 51 which has threaded engagement with an opening 42 and abuts against the outer face of section 12. The plates 49 and holdfast devices 51 provide terminals for circuit wire connections not shown.

Carried by and arranged in the inner face of the portion 44 of the part 14 are four annular

contacts (only two of which are shown) and which are arranged in pairs. The annular contacts of each pair are disposed in spaced alignment. The annular contacts of the pair shown are designated 52, 53 and the said four annular contacts are mounted in the grooves 29 and extend into the sockets 39, as well as being arranged in the path of circuit closures to be presently referred to. The annular contacts 52, 53 of each pair are electrically connected together by a strip of conducting material 54 as represented by the dotted line showing, Figure 1. The annular contact 53 of each pair is provided with an outwardly directed stem 55 of conducting material. The stems 55 are of a length to extend into the cutouts 32, 33 at the inner ends of the bases of these latter and are connected by the holdfast devices 56 to the portion 41 of part 14. The stems 55 and holdfast devices 56 provide terminals for circuit wire connections.

Within each of the sockets 39 is arranged a rectangular shiftable circuit opening and closing member 57 which is to bridge and coact with a contact 52 or 53. Carried by the member 57 is a threaded stem 58 which operates through the passage 21. Surrounding the stem 58, abutting the member 57 and also abutting the shoulder 24 is a coiled controlling spring 59 which functions when the member 57 is released in a manner to be referred to to shift the member 57 clear of the contact 52 or 53. The stem 58 is peripherally threaded.

The lug 36 is to prevent flash over from contact 52 to contact 53.

When all stems 58 are released, the fuse block 35 or fuse panel is absolutely dead front.

A contact 52 and 53, a passage 21, a groove 19, a set of teeth 25, a cutout 18 and a socket 39 constitute the stationary section of an adapter. The latter is formed of two sections, one the stationary section referred to and the other a movable section consisting of a circuit opening and closing member 57, a stem 58 and a spring 59.

The block 10 as shown, will be provided with four adapters and there will be associated with each adapter a fuse plug which is to be detachably connected with the adapter. Owing to the manner in which the adapter is set up it cannot be tampered with. The fuse plug is generally indicated at 60 and includes a body part 61 formed of porcelain, Bakelite or other suitable non-conducting material. The body part 61 is of tubular form and is provided with a socket 62 opening at its outer end. The socket 62 is of materially less length than that of body part 61 and has its inner portion, indicated at 63, gradually decreasing in diameter towards its inner end. The inner or base wall of socket 62 is indicated at 64. The body part 61, at its outer end, is formed with a laterally disposed annular flange 65 having its edge provided with diametrically disposed grooves 66 of like form and each includes a pair of side walls and an inner wall. Each side wall has a narrow outer portion and a wide inner portion. The inner wall includes an outer straight portion and an inwardly inclined inner portion. The outer portion of the side walls merge into the outer straight portion of the inner walls. The wide inner portions of the side walls merge into the inclined inner portions of the inner wall. The inclined portions of the inner walls are indicated at 67. The body part 61 has a reduced inner portion 70 thereby forming said body part 61 with a peripheral

shoulder 71. The inner end of the reduced portion 10 of the body part 61 is formed with a socket 72 and with teeth 73. The body part 61, axially thereof, is formed with a circular bore 14 which extends from the base 64 of socket 62 to the base of socket 72. Anchored to the bore 14 is an interiorly threaded tubular member 75 open at its inner end, toothed on its inner edge, as at 75a, (Figures 1 and 4) and which merges at 10 its outer end into a disc 76, of greater diameter than said member. The disc 76 seats upon the base 64 of socket 62. A fuse element, indicated at 77, includes a flat stretch 78 seated upon the disc 76 and a curved stretch 79 merging at 15 one end into one end of the stretch 78 and at its other end into a stretch 80 embedded in the body part 61. The stretch 80 merges into an annulus 81 which forms a part of element 77, surrounds the reduced portion 10 and bears 20 against the shoulder 71. The stretch 78 of the fuse element 77 is anchored upon and to the disc 76 by a body 82 of cementitious material. Seated upon the outer end of body part 61 is a transparent closure 83 for the outer end of the socket 25 et 62. A retaining cap for the closure 83 is indicated at 84 and which is formed with inherent diametrically opposed bendable arms 85 for mounting in the grooves 66 and bent to engage the wall portion 67 of the grooves 66 whereby the 30 closure 83 and cap 84 are connected to body part 61. The element 77 has spaced weakened parts.

When the fuse plug 60 is connected to the block 10 the member 75 extends upon the stem 58 and 35 on revolving plug 60 the threads of member 75 will coact with the threads on stem 58 to provide for the shifting of member 57 to the position shown in Figure 2, whereby said member 57 will engage with a contact 52 or 53 and such position of member 57 will be had against the action 40 of spring 59. When plug 60 is seated in the block 10 it is arranged in co-relation with respect to the adapter. The reduced inner end 10 of body part 61 will extend into cutout 18 and also 45 into the groove 19. The annulus 81, which surrounds the reduced portion 10 of body part 61 will seat against a contact 47. When the fuse plug 60 is coupled to the block 10 the inner end edge of the portion 10 will oppose and be spaced 50 from the inner wall of groove 19. When the fuse plug 60 is connected to the block 10 a portion of part 14, indicated at 86, will extend into the socket 72.

When the fuse plug 60 is connected to the block 55 the teeth 73 will extend inwardly beyond and in surrounding relation with respect to the teeth 25. The teeth 25 will be arranged outwardly beyond and in surrounding relation with respect to the teeth 75a. The teeth 25, 73 and 75a function to tear or disrupt any foreign body or bodies, such as lead foil, small wire, etc. that may be placed in the fuse 60, socket 16 or part 14 of block 10 or an adapter 89 to be referred to for the purpose of tampering with the fuse plug assembly.

The fuse plug assembly shown in Figures 3 to 9 is of the type for connection to the form of fuse block or panel now in general use. The assembly shown in Figures 5 and 6 is generally indicated 70 at 81 and consists of a fuse plug 88 and an adapter 89. The fuse plug 88 is of the same construction as the fuse plug 60 and the description of the latter is to apply to the description of the plug 88. The adapter 89 is of a type which is to be

secured in a non-removable position with respect to the block or panel in which it is to be extended. The adapter 89, when in secured position, cannot be tampered with. The adapter 89 includes a threaded sleeve 90 of conducting material formed 5 with a pair of diametrically opposed rectangular slots 91, 92 in proximity to its inner end. The sleeve 90, at its outer end, is formed with an inwardly extending annular flange 93. The sleeve 90 encompasses the body part of the 10 adapter and said body part consists of a forward and a rear section 94, 95 respectively, arranged in endwise abutting relation and formed of porcelain, Bakelite or other suitable non-conducting material. The section 94, at its outer end, is formed with a circular cutout 96 which corresponds to the cutout 18 formed in the part 14 of the block 10. The section 94 is provided with an annular groove 97 which opens into the cutout 96 and which corresponds to a groove 19 in the 15 part 14 of the block 10. The outer wall 97a of groove 97 is flush with the wall of the cutout 96. The section 95 has its rear end provided with a rectangular socket 98 in which is arranged a 20 yoke-shaped member 99 of conducting material having its arms 100 extended forwardly and provided at their forward ends with oppositely disposed inwardly extending flanges 101 which seat in grooves 102 formed in the forward or base wall 25 of the socket 98. A yoke-shaped insulating member 103 is mounted against the inner sides and forward face of the base of the member 99. The member 103 is spaced from the flanges 102 and 30 said flanges constitute contacts and extend into the socket 98 in the path of a shiftable spring controlled circuit closure to be presently referred to. The section 94 has an axial bore 104 with its wall formed of two different diameters. The larger diameter wall portion is indicated at 105 40 and opens into socket 98 and the smaller diameter wall portion is designated 106 and communicates with the cutout 96. The junction of the two diameters of wall portion provides the section 94 with an internal shoulder 107. The section 45 94, at a point thereof bordering the outer end of the bore 104 and the inner wall of the groove 97, is formed with a row of teeth 108.

The section 95 has an axial opening 109 through which extends a holdfast means 110 threadedly 50 engaging in the base of the member 99.

Shiftable within the socket 98 is a spring controlled circuit opening and closing member or element 111 for engaging with the flanges 102 for the purpose of closing the circuit. Integral 55 with the member 111 and extending through the bore 104 is a peripherally threaded stem 112 for threaded engagement with the interiorly threaded tubular member 113 of the fuse plug 88. Interposed between the shoulder 107 and the member 111, as well as surrounding the stem 112 is a coiled controlling spring 114 for the member 111. The spring 114 functions to shift the member 111 clear of the flanges 102 when the stem 112 is released from the tubular member 113. The latter functions in connection with the threads of the stem to shift the member 111 to and to hold it in circuit closing position relative to the flanges 102.

The section 94 has arranged therein a pair of 70 oppositely disposed spring controlled locking members 115, 116 provided with pointed locking bars 117, 118 for extension through the slots 91, 92 respectively and which are capable of engaging in the material of the fuse block or panel 75

in which the adapter 89 is mounted for the purpose of locking the adapter 89 to prevent it from being removed and from being tampered with.

The adapter shown in Figure 6 is substantially the same in construction as the adapter shown in Figure 2 with the exception that the construction 101 will provide the flanges instead of an annulus. The fuse plug 88 is arranged relative to the adapter 89 in the same manner as the fuse plug 88 is arranged relative to an adapter shown in Figure 2.

With reference to Figure 2, the part 14 of the block 18 is provided with a ground attachment bar, as indicated at 120, to which all neutral wires are attached.

Each contact 47 is an outer contact or outer contact means. Each contact 52 or 53 is an inner contact or inner contact means. The flange 93 is an outer contact or outer contact means. The flanges 101 provide an inner contact or inner contact means.

The threaded holdfast devices 50 are exposed when panel cover is open for the purpose of testing and replacing fuses.

The fuses intended to be used will have threads of a different pitch on those up to 15 amperes capacity than those fuses of a capacity of 30 amperes. This is to prevent the use of a 30 ampere fuse where the value should only be 10 or 15 amperes.

What we claim is:

1. In a fuse plug assembly, a rotatable plug-like element of non-conducting material, said element being formed with a socket and an axial opening communicating with the socket, said element being formed with a peripheral shoulder, a fixed interiorly threaded tube in said opening and having a closed end positioned within said socket, a fuse anchored to said end, arranged in said socket, extending through the plug body and abutting said shoulder, and an adapter structure for receiving said element, said structure including a body of non-conducting material formed with a socket and a passage opening into the latter for receiving said tube, an outer contact on said body for coaction with said fuse, a shiftable spring controlled circuit opening and closing member within the socket of said body, an inner contact for coaction with and normally free of contacting relation with said member, and a peripherally threaded stem carried by said member, arranged in said passage for threaded engagement with the threads of said tube, on the rotation of said element in one direction to provide respectively for the coupling of said element and body together; the shifting of said member to engage said inner contact; and for the contacting of the fuse with said outer contact.

2. In a fuse plug assembly, a rotatable plug-like element for coupling to an adapter, said element being formed with a socket and an axial opening having one end communicating with said socket, said element being formed with a peripheral shoulder, a fixed interiorly threaded tube in said opening adapted to threadedly engage with the adapter to couple the latter and element together, said tube having a closed outer end arranged within said socket, said tube having an open inner end, a fuse having a stretch anchored to said closed end, a stretch arranged in said socket, a stretch extending through the body of said element and a stretch arranged against said shoulder, said tube having a portion extended inwardly from the other end of said opening.

3. In a fuse plug assembly, a rotatable plug-

like element for coupling to an adapter, said element being formed with a socket and an axial opening having one end communicating with said socket, said element being formed with a peripheral shoulder, a fixed interiorly threaded tube in said opening adapted to threadedly engage with the adapter to couple the latter and element together, said tube having a closed outer end arranged within said socket, said tube having an open inner end, a fuse having a stretch anchored to said closed end, a stretch arranged in said socket, a stretch extending through the body of said element and a stretch arranged against said shoulder, said tube having a portion extended inwardly from the other end of said opening, 15 said socket opening at the outer end of said element, said element being formed with a socket opening at the inner end thereof and having its wall encompassing in spaced relation the extended portion of said tube. 20

4. In a fuse plug assembly, a rotatable plug-like element for coupling to an adapter, said element being formed with a socket and an axial opening having one end communicating with said socket, said element being formed with a peripheral shoulder, a fixed interiorly threaded tube in said opening adapted to threadedly engage with the adapter to couple the latter and element together, said tube having a closed outer end arranged within said socket, said tube having an open inner end, a fuse having a stretch anchored to said closed end, a stretch arranged in said socket, a stretch extending through the body of said element and a stretch arranged against said shoulder, said tube having a portion extended inwardly from the other end of said opening, 30 said socket opening at the outer end of said element, said element being formed with a socket opening at the inner end thereof and having its wall encompassing in spaced relation the extended portion of said tube, and said element being formed at its inner end with a row of teeth encompassing in spaced relation the extended end of said tube. 35

5. In a fuse plug assembly, a rotatable plug-like element for coupling to an adapter, said element being formed with a socket and an axial opening having one end communicating with said socket, said element being formed with a peripheral shoulder, a fixed interiorly threaded tube in said opening adapted to threadedly engage with the adapter to couple the latter and element together, said tube having a closed outer end arranged within said socket, said tube having an open inner end, a fuse having a stretch anchored to said closed end, a stretch arranged in said socket, a stretch extending through the body of said element and a stretch arranged against said shoulder, said tube having a portion extended inwardly from the other end of said opening, 55 said element being formed with a laterally extending flange at its outer end having its edge formed with grooves, the inner walls of said grooves having inwardly extending inclined parts, said socket opening at the outer portion of said element, a transparent closure on the outer end of said element for said socket, and means for securing said closure to said element, said means having inherent parts binding against said walls for anchoring it to said element. 65

6. In a fuse plug assembly, an adapter for coupling to the plug of the assembly, said adapter including a body of non-conducting material formed with a socket, a cutout at its outer end, a groove opening into said cutout and a passage 70

- communicating at its inner end with said socket and at its outer end with said cutout, an outer contact at the outer end of said body bordering said cutout, an inner contact at the inner wall of said socket, a spring controlled circuit opening and closing member within said socket for coaction with and normally free of contacting relation with said inner contact, and a shiftable structure for and carrying said member, said structure including a peripherally threaded plug engaging element extending through said passage for threadedly engaging the plug for coupling the latter to the adapter.
7. In a fuse plug assembly, an adapter for coupling to the plug of the assembly, said adapter including a body of non-conducting material formed with a socket, a cutout at its outer end, a groove opening into said cutout and a passage communicating at its inner end with said socket and at its outer end with said cutout, an outer contact at the outer end of said body bordering said cutout, an inner contact at the inner wall of said socket, a spring controlled circuit opening and closing member within said socket for coaction with and normally free of contacting relation with said inner contact, a shiftable structure for and carrying said member, said structure including a peripherally threaded plug engaging element extending through said passage for threadedly engaging the plug for coupling the latter to the adapter, said body being formed with a row of teeth bordering said opening and groove.
8. In a fuse plug assembly, an adapter for coupling to the plug of the assembly, said adapter including a body of non-conducting material formed with a socket, a cutout at its outer end, a groove opening into the cutout, a passage communicating at its inner end with said socket and at its outer end with said cutout, a threaded shell of conducting material encompassing said body and having an inwardly extending flange at its outer end constituting an outer contact seated against the outer end of said body and bordering said cutout, an inner contact at the inner wall of said socket, a spring controlled circuit opening and closing member within said socket for coaction with and normally free of contacting relation with said inner contact, and a shiftable structure for and carrying said member, said structure including a peripherally threaded plug engaging element extending through said passage for threadedly engaging the plug for coupling the latter to the adapter.
9. In a fuse plug assembly, an adapter for coupling to the plug of the assembly, said adapter including a body of non-conducting material formed with a socket, a cutout at its outer end, a groove opening into the cutout, a passage communicating at its inner end with said socket and at its outer end with said cutout, a threaded shell of conducting material encompassing said body and having an inwardly extending flange at its outer end constituting an outer contact seated against the outer end of said body and bordering said cutout, an inner contact at the inner wall of said socket, a spring controlled circuit opening and closing member within said socket for coaction with and normally free of contacting relation with said inner contact, a shiftable structure for and carrying said member, said structure including a peripherally threaded plug engaging element extending through said passage for threadedly engaging the plug for coupling the latter to the adapter, and said body being

formed with a row of teeth bordering said opening and groove.

10. In a fuse plug assembly, an adapter for coupling to the plug of the assembly, said adapter including a body of non-conducting material formed with a socket, a cutout at its outer end, a groove opening into the cutout, a passage communicating at its inner end with said socket and at its outer end with said cutout, a threaded shell of conducting material encompassing said body and having an inwardly extending flange at its outer end constituting an outer contact seated against the outer end of said body and bordering said cutout, and inner contact at the inner wall of said socket, a spring controlled circuit opening and closing member within said socket for coaction with and normally free of contacting relation with said inner contact, a shiftable structure for and carrying said member, said structure including a peripherally threaded plug engaging element extending through said passage for threadedly engaging the plug for coupling the latter to the adapter, said shell being formed with spaced slots, and oppositely disposed spring controlled locking devices carried by said body and extendible through said slots.
11. In a fuse plug assembly, an adapter for coupling to the plug of the assembly, said adapter including a body of non-conducting material formed with a socket, a cutout at its outer end, a groove opening into the cutout, a passage communicating at its inner end with said socket and at its outer end with said cutout, a threaded shell of conducting material encompassing said body and having an inwardly extending flange at its outer end constituting an outer contact seated against the outer end of said body and bordering said cutout, an inner contact at the inner wall of said socket, a spring controlled circuit opening and closing member within said socket for coaction with and normally free of contacting relation with said inner contact, a shiftable structure for and carrying said member, said structure including a peripherally threaded plug engaging element extending through said passage for threadedly engaging the plug for coupling the latter to the adapter, said body being formed with a row of teeth bordering said opening and groove, said shell being formed with spaced slots, and oppositely disposed spring controlled locking devices carried by said body and extendible through said slots.

12. In a fuse plug assembly, a fuse block formed of inner and outer interengaging connected together sections of non-conducting material, said outer section being formed in its outer face with a pair of outer sockets arranged in lateral communicating relation and with one of greater area than the other, a cutout inwardly of and opening into the socket of greater area through the bottom of the latter, an outer groove inwardly of and opening into the cutout through the bottom of the latter, an inwardly directed passage extending from said cutout, an inner groove in its inner face, a rear groove encompassing said passage adjacent to said inner groove, an opening leading from the outer socket of smallest area to said inner groove and a pair of spaced vertical cutouts communicating at their bases with said inner groove; and said inner section being formed on its outer face with an inherent part of less depth than and extended into said inner groove, and a rear socket into which said passage and rear groove open.

13. In a fuse plug assembly, a fuse plug block

- formed of a body of non-conducting material provided with an outer and an inner socket and communicating means between said sockets, said outer socket for receiving the fuse plug, an outer contact in the form of an annulus seated upon a wall of the outer socket and for coaction with the fuse of the plug, an inner contact in the form of an annulus mounted in a wall of the inner socket, a conductor positioned in said body connected to the inner contact, a second conductor in said body, means for electrically connecting said second conductor to said outer contact, a spring controlled circuit opening and closing member within said inner socket for coaction with and normally free of contacting relation with said inner contact, and a shiftable structure for and carrying said member, said structure including a peripherally threaded element operating in said communicating means for coupling the plug to the block.
14. In a fuse plug assembly, a fuse plug block formed of a body of non-conducting material provided with an outer and an inner socket and

communicating means between said sockets, said outer socket for receiving the fuse plug, an outer contact in the form of an annulus seated upon a wall of the outer socket and for coaction with the fuse of the plug, an inner contact in the form of an annulus mounted in a wall of the inner socket, a conductor positioned in said body connected to the inner contact, a second conductor in said body, means for electrically connecting said second conductor to said outer contact, a spring controlled circuit opening and closing member within said inner socket for connection with and normally free of contacting relation with said inner contact, a shiftable structure for and carrying said member, said structure including a peripherally threaded element operating in said communicating means for coupling the plug to the block, and said communicating means being formed to receive the inner end of the fuse plug when the latter is coupled to the block by 20 said element.
